(57) CLAIM

I claim the ornamental design for a phone cover, as shown and described.

DESCRIPTION

FIG. 1 is a rear, bottom, right perspective view of a phone cover my new design;

FIG. 2 is a rear elevational view thereof;

FIG. 3 is a front elevational view thereof;

FIG. 4 is a right elevational view thereof;

FIG. 5 is a left elevational view thereof;

FIG. 6 is a top plan view thereof;

FIG. 7 is a bottom plan view thereof; and,

FIG. 8 is a rear, top, right perspective view thereof with an optional insert shown.

The broken lines in the drawings illustrate portions of the phone cover which form no part of the claimed design.
